UNITED STATES PATENT OFFICE.

THOMAS E. SHEVILL, OF NEW YORK, N. Y.

CURTAIN-HANGING APPARATUS.

No. 876,405.

Specification of Letters Patent.

Patented Jan. 14, 1908.

Application filed November 10, 1905. Serial No. 286,642.

To all whom it may concern:

Be it known that I, THOMAS E. SHEVILL, a citizen of the United States, residing in the borough of Brooklyn, city of New York, in the county of Kings and State of New York, have invented certain new and useful Improvements in Curtain-Hanging Apparatus, of which the following is a specification.

The invention relates to means for suspending draperies, and more particularly light ornamental stuffs such as lace curtains.

The object of the invention is to provide a suspending means which shall be attractive in appearance, permit the curtains to be easily and quickly introduced and adjusted, with any surplus in length neatly disposed and concealed, and especially adapted for the reception and ready adjustment and arrangement of the double curtains frequently employed.

The invention consists in certain novel features, details of construction and arrangement of parts by which the above objects are attained, to be hereinafter described.

The accompanying drawings form a part of this specification and show an approved form of the invention.

Figure 1 is a plan or top view of the apparatus before the introduction of the curtains.

Fig. 2 is a corresponding vertical transverse section, taken on the line 2—2 in Fig. 1, but showing a portion of a curtain in place. Fig. 3 is a horizontal section on the line 3—3 in Fig. 2, partly in plan view and without a curtain. Fig. 4 is a perspective view showing a portion of the apparatus with two curtains therein lapped one upon the other at their inner or adjacent margins, and Fig. 5 is a vertical section corresponding to the preceding figure, the plane of section being indicated by the line 5—5 thereon.

Similar letters of reference indicate the same parts in all the figures.

A and A¹ are bars of wood or other suitable material extending transversely of the upper portion of the window, door or other opening, forming in effect a curtain-rod, supported at the ends in sockets or apertures b b in brackets B B secured to the window-frame by screws or otherwise. The curtains M M are suspended from the bars, being received

therein and held frictionally as will be described.

The brackets are of metal sufficiently elastic to permit their forcible separation in introducing the bars, as indicated by the dotted lines in Fig. 3, and each is provided on the outer face with an ornamental cap C, hiding the ends of the bars and held in place by the engagement of the lugs B¹ B¹ on the brackets with holes c c in the caps.

Screws or pins A³ set radially in the bars near their ends are received in notches b² in cam-like projections B² on the brackets and serve to hold the bars against revolving and endwise movements. The screws may also serve with or without other fastening means in securing the bars together at the ends.

The bars A and A¹ are preferably each segmental in cross-section, making a complete cylinder when applied together, the line of separation formed by their adjacent plane faces being a chord, whereby one bar is heavier than the other, the heavier A lying normally below the lighter bar A¹, and the adjacent plane faces forming the line of the chord extends from a point in the upper semi-circumference of the circle rearwardly and downwardly to a point in or near the lower semi-circumference, as shown in the drawings.

In hanging the curtain its upper edge is passed over the bar A¹ from the front and between the bars from the rear, the bars being sprung apart to permit the insertion, drawn through to the front and following the cylindrical surface of the bars lies beneath the main portion of the curtain, the friction due to the contact of the two portions of the curtain thus conditioned aided by the sharp bend about the rear edge of the bar A¹ holds the curtain reliably, and any downward strain increases the tension and is successfully resisted; conversely by lifting the main portion of the curtain out of contact with the clamped portion the tension is relaxed and any adjustment as to length of the depending portion and also any lateral adjustment may be easily effected.

Any considerable excess of length which otherwise would hang in rear of the main curtain and detract from the appearance is

grasped at the end between two clamping-
rods $D^1 D^1$, held in strong contact by the loops
 $D^2 D^2$ encircling the ends of both, and rolled
or wound thereon, preferably in reverse di-
5 rection to the path around the bars $A A^1$ so
that the portion of the excess extending
tangentially from the lower face of the bar A
shall extend to the lower face of the roll D
thus formed, which is then placed in rear of
10 the bars and is supported by the engage-
ment of the projecting ends of the rods in
notches $b^1 b^1$ in the brackets, the notches
being so shaped as to hold the roll against
unwinding. Thus conditioned the excess is
15 neatly and conveniently disposed of and
effectually hidden from view.

In order to further conceal the roll D , the
notches $b^1 b^1$ are elevated so as to hold the
rods $D^1 D^1$ somewhat above the bars $A A^1$ in
20 such relation to the latter that unless the sur-
plus length be excessive, the portion between
the bar A and roll D will extend in an upward
inclination less liable to observation by per-
sons in the room.

25 So far as yet described the bars $A A^1$ may
have a single slit or narrow opening between
them in which the curtain is received, and if
double curtains are to be hung the overlap-
ping margins will lie one upon the other in
30 such single opening. The apparatus may be
thus used successfully but the adjustment of
the two curtains individually, sidewise and
vertically, is difficult by reason of the fric-
tion and entanglement of the overlapping
35 surfaces; tending to displace one curtain in
adjusting the other. To obviate this diffi-
culty a thin strip F of wood, metal or other
material extending longitudinally is placed
between the plane faces of the bars A and A^1
40 and held at the ends by the same screws or
nails that hold the bars together, thus forming
two narrowly separated slits each adapt-
ed to receive a curtain. The two curtains are
introduced as before but each in its own
45 opening and both may be adjusted, as to
length and the extent of overlap, independ-
ently without interference. Any excess length
is concealed as before on the rods $D^1 D^1$.

The apparatus is simple, inexpensive,
50 easily applied and operated, and presents an
attractive appearance. The caps $C C$ covering
the projecting portions of the brackets
and the ends of the bars and rods, may be
ornamented as desired.

55 Although I have described the bars as held
stationary in the brackets, and the introduc-
tion of the curtains as practiced with the bars
thus conditioned, it will be understood that
the brackets may be readily sprung apart to
60 release the pins $A^3 A^3$ and permit the bars to
be partially revolved to present the slits or
narrow openings as may be desired, and again turned to place after the introduction

of the curtains, or the bars may be wholly
separated from the brackets if deemed de-
sirable. The exact disposition of the cur-
tains is facilitated by arranging them as de-
sired with the bars in the position they are
intended normally to occupy.

65 Modifications may be made in the forms
and proportions of the parts without depart-
ing from the principle or sacrificing the ad-
vantages of the invention, and parts may be
used without the whole. As indicated
70 above, the strip or partition F may be
omitted and two curtains inserted in the
single opening between the bars.

75 Other means for disposing of and concealing
the excess length of the curtain or curtains
may be employed or the loose ends may
hang in the rear of the main portions.

80 I attach importance to the transverse in-
clination of the slit or opening in relation to
the outer surface of the bars whereby the
frictional contact of the surfaces of the cur-
tains 85 tending to move in opposite direction
under downward strain on the main portion,
is increased by such strain and thus resisted.

85 Although I have described the bars $A A^1$
as segmental, forming together a cylindrical
support, and consider such form preferable,
it will be understood that the cross-section
may be octagonal, hexagonal or other form,
and the angular inclination of the slits or
90 openings between the bars, when in position,
may be varied, inducing a corresponding va-
riation in the area of the frictionally contact-
ing surfaces of the curtain and thereby in-
creasing or decreasing the resistance to
strain.

100 I claim:—

1. In a curtain-hanging apparatus, a pair
of bars having plane flat adjacent faces, a flat
plane-faced partition between said adjacent
faces, said bars and partition adapted to hold
a curtain in flat contact with and between
105 them, brackets in which said bars are sup-
ported, clamping-rods adapted to grasp the
end of a curtain and receive the excess length
in a roll thereon, sockets on said brackets to
receive said rods and support them and said
roll, and caps on the exterior faces of said
brackets, serving to cover the latter and the
ends of said bars and rods.

110 2. In a curtain-hanging apparatus, a pair
of bars having plane flat adjacent faces, a flat
plane-faced partition between said adjacent
faces, said bars and partition adapted to hold
a curtain in flat contact with and between
115 them, brackets in which said bars are sup-
ported, clamping-rods adapted to grasp the
end of a curtain and receive the excess length
in a roll thereon, sockets on said brackets ar-
ranged to receive said rods and support them
120 and said roll, and fixed means extending lat-
erally from one of said bars to engage fixed

means on said brackets and constructed to prevent turning of said rods therein.

3. In a curtain-hanging apparatus, a pair of bars having plane faces applied together, brackets having apertures in which the ends of said bars are received, cam-surfaces on the inner faces of said brackets, a notch in each of said cam-surfaces, a pin at each end of said bars arranged to contact with said cam-sur- 10 faces and spring said brackets apart as said

bars are revolved, and to be engaged in said notches by the return movement of said brackets, to hold said bars against turning.

In testimony that I claim the invention above set forth I affix my signature, in presence of two witnesses.

THOMAS E. SHEVILL.
